Application April 24, 1956, Serial No. 580,285

1 Claim. (Cl. 336—212)

This invention relates to transformer construction and relates particularly to a multi-leaved core construction having numerous structural assembly and operating advantages.

In the manufacture of transformers having a laminated core, it has long been common to fabricate said cores by punching the individual laminae from sheet material, applying the transformer windings to a portion of the stacked laminae or core parts, and then to assemble the core in operating relationship within an encircling frame member. For purposes of economy of both material and labor, there has long been developed several types of transformers, of which one is shown by U. S. Patent No. 1,297,161, wherein the core and frame members are stamped from a single sheet of metal and the core pieces are arranged in an H-shape so that the winding may be applied around the web of the H and be held in place by the flanges thereof.

In studying the design of this general type of transformer, I have found that a number of important features have apparently been overlooked in previous designs of this character. These features, while not all unusual by themselves, when taken together in the overall pattern hereinafter discussed further, result in a transformer having unexpectedly desirable properties. Particularly, since these features often point in conflicting directions, insofar as their functional results are concerned, I have discovered a point at which they can be balanced with excellent results.

Particularly, it is desirable to have the line of discontinuity between the core structure and the surrounding frame structure as long as possible in order to minimize the flux intensity at any point at which flux lines pass from one member across the line of discontinuity to the other member, whereby reluctance losses are minimized. Further, it is desired to have the flanges on each side of the web or cross bar of the above mentioned core pieces long enough to receive the full amount of the winding and protect it to a maximum extent, yet without extending such flanges beyond the point at which they are functionally advantageous. On the other hand, too much extension of said flanges will result in unreasonable weakening of them and will present both stamping and assembly problems.

Accordingly, a principal object of the invention has been to provide a transformer construction of maximum magnetic efficiency with minimum of mechanical fabrication and assembly problems.

A further object of the invention has been to provide a transformer, as aforesaid, in which the flux density at all points where lines of flux pass a line of discontinuity between portions of metal carrying such flux is reduced to a minimum, but wherein said reduction remains consistent with easy mechanical fabrication and assembly.

A further object of the invention has been to provide a transformer, as aforesaid, whose general arrangement and construction is sufficiently like presently known trans-

2

formers that it will be readily accepted by the market and will be readily accepted and understood by manufacturing, utilizing and service personnel.

A further object of the invention has been to provide a transformer, as aforesaid, which can be manufactured at a very low cost.

A further object of the invention has been to provide a transformer, as aforesaid, so designed that dimensional variations between the parts occurring during the fabrication thereof, such as variations occurring by the wearing of the punching dies, will be either self-compensating or will be self-absorbing and will therefore not interfere with the assembly and accurate inter-fitting of the parts.

A further object of the invention has been to provide a transformer, as aforesaid, wherein the winding can be rapidly applied thereto and will be adequately protected when in operating position.

A further object of the invention has been to provide a transformer, as aforesaid, which will be sturdy and capable of long and reliable use.

Other objects and purposes of the invention will be apparent to persons acquainted with devices of this general type upon reading the following disclosure and inspecting the accompanying drawings.

25 In the drawings:

Figure 1 is an oblique view of a transformer embodying the invention.

Figure 2 is a sectional view taken along the line II—II of Figure 1.

30 Figure 3 is an enlarged fragment of Figure 2.

Figure 4 is a fragment of Figure 2 showing an alternate construction.

General description

35 The invention provides a transformer 10 (Figures 1 and 2) having a core 9 comprised of an outer frame portion 11 and a generally H-shaped inner portion 12. A transformer winding 13 is placed around the inner portion 12 and is confined between the flanges thereof.

40 Insulation members are here provided between three sides of the winding and the core and an insulating air gap is provided on the fourth side.

Detailed construction

45 The outer portion 11 of the transformer core 9 is comprised of a plurality of preferably identical, laminated plates 16 which are generally rectangular in shape. The plates 16 are assembled or stacked to form a unitary structure and are held together by elongated fasteners 17 adjacent to the four corners thereof. The fasteners in this particular embodiment are tubes of suitable length which extend through openings 15 in said plates and which are flared at their ends to prevent dislodgement of the plates. It is apparent that other types of fasteners suitable for this purpose may be used, if desired. The plates 16 are each provided with a central opening 18 having first and second edges 20 and 21, respectively, which are substantially straight, equal in length and parallel with the end edges of the plate 16. The opening 18 has third and fourth edges 22 and 23, respectively. Each of the edges 22 and 23 has a concave, arcuate portion 24, which is preferably circular or elliptical in shape, comprising the major extent of the length thereof.

55 The curvature of each portion 24 is such that, if extended, it would intersect the adjacent ends of the first and second edges 20 and 21, respectively. However, at a point close to the respectively adjacent ends of the first and second edges, the radius of curvature of portion 24 is progressively shortened in the region 26 until the curved edge intersects an imaginary line connecting corresponding ends of the first and second edges 20 and 21. The end portions 27 of each of said edges

22 and 23 consist in this particular embodiment of straight segments lying along said imaginary line. Said end portions may, however, be provided with any desired shape.

The inner portion 12 of the transformer core consists of a plurality of laminated, generally H-shaped plates 30. The plates 30 are identical and each have flanges 28 and 29 with convexly arcuate outer edges 31 and 32 which conform to the arcuate, concave shape of portion 24 and region 26 of the edges 22 and 23. In fact, the inner portion 12 may be stamped from the outer portion 11 to provide at least a part of the opening 18, thereby facilitating economical and speedy fabrication as well as to effect, and maintain even through various stages of die wear, a snug fit between said convex and concave edges. As a result of the H-shape of the plates 30, the edges 34 and 35 of the web 36 in each inner plate 30 are spaced from the corresponding, opposing edges 20 and 21, respectively, for receiving the winding 13 therebetween. Removal of the metal which produces this spacing is also accomplished during the stamping operation. The plates 30 are held in their laminated assembly by fasteners 33, which are of any convenient nature, such as bolts.

The plates 16 and 30 are provided with mating recesses 37 which define a passageway, if desired, for a stacking key 38, which key may be subsequently affixed permanently in place, or removed, as desired. Thus, the plates 16 and 30 must be oriented properly before they can be assembled on the stacking key.

The flanges 28 and 29 of plates 30 are of sufficient length that the entirety of the transformer winding 13 can be received therebetween to provide side support for the entire radial extent of that portion of said winding which lies between said flanges. The winding 13 may, if desired, be covered by any suitable protective cover 40, such as varnish. A pair of channel-shaped jackets 41, which are made of insulating material engage the said winding 13 on three sides and are provided with an open fourth side facing the edges 21 and 22 of frame portion 11. The outer edges 45 and 46 of each of the jackets converge toward each other to retain the winding 13 therewithin and engage the edges 20 and 21 of plates 16 to space the winding 13 from said edges and thereby maintain an air gap 47 therebetween. Said edges 45 and 46 are preferably slightly wider than the width of the air gap 47 and sufficiently resilient both to maintain the desired spacing and to absorb manufacturing variations between the parts. Alternatively, the edges 45 and 46 may be extended, if desired and as indicated at 45' and 46' in Figure 4, to overlap each other and thereby provide positive insulation of the winding from the face 20 instead of the air gap 47.

The engagement of the edges 31 and 32 of the inner

plates 30 with the edges 22 and 23, respectively, of the outer plates 16 provides lines and areas of discontinuity between the inner portion 12 and the outer portion 11 of the core 9. Since these areas are curved away from the center of the transformer core 9, they provide the least possible flux intensity per unit of area while avoiding undesirable concentrations of flux in any given area. Also, the shape of the portions 11 and 12 provides the maximum permissible area of discontinuity available in this type of transformer which is commensurate with efficient manufacturing practices.

Although a particular, preferred embodiment of the invention has been disclosed above for illustrative purposes, it will be understood that variations thereof within the scope of such disclosure are fully contemplated unless specifically stated to the contrary in the appended claim.

I claim:

A transformer construction of the laminated core type, including in combination: a plurality of core elements 20 arranged in superposed relationship, each of said elements including an external frame member having a central opening therewithin, said central opening having first and second parallel, substantially straight sides and third and fourth concavely curved sides facing each other; 25 a generally H-shaped inner member with the remote edges of the legs thereof being curved to fit snugly against said third and fourth sides of said frame member, said legs extending to points spaced a slight distance from said first and second sides; a pair of channel-shaped 30 insulating members, the webs of said channel-shaped members lying adjacent the respective edges of the web of said inner member, said channel-shaped members opening toward said first and second sides, respectively, with the outer ends of the legs thereof being curved 35 toward each other and positioned against said first and second sides; transformer winding means wrapped around the webs of said inner member and said channel-shaped members, said winding means being of approximately the same depth as the depth of the legs of the inner member and lying within said channel-shaped members, said depth of said winding means being materially less than the depth of said legs of said channel-shaped members, whereby the outer ends of the legs of said channel-shaped members maintain the outer edges of said winding 45 means spaced from said first and second sides to provide an air gap therebetween.
